HEIGHT LEVEL CONTROL FOR SHEETS BEING STACKED

Calvin L. Vansickle, Dundas, Ontario, Canada, assignor to Dominion Foundries and Steel Limited, Hamilton, Ontario, Canada

Application June 14, 1956, Serial No. 591,324

2 Claims. (Cl. 214—6)

This invention relates to a device for automatically controlling the height level of stacked steel sheets and the like and wherein the stack is formed by successively placing sheets upon the top of the stack as the sheets are delivered from sheet shearing apparatus, as used in steel strip mills.

In standard practice lengths of steel strip continuously travel to the shearing apparatus where they are sheared to produce sheets of desired size, the sheets then traveling upon a conveyor belt or the like for successive stacking delivery unto the top of a stack of sheets carried upon a vertically moveable platform which is manually controlled in downward movement, the top of the stack being maintained at a level slightly below the plane of sheet delivery from the conveyor to the top of the stack and whereby the delivered sheets only have a short drop, irrespective of the number of sheets in stack.

In the foregoing arrangement the stack supporting platform is generally mounted upon the ram of a hydraulic lift, the platform being lowered through the manual manipulation of a valve mechanism controlling the bleeding of hydraulic fluid from the lift; and the object of this invention is to provide a pneumatic arrangement automatically actuated by the height of the stack of sheets on the platform, and which actuation controls the bleeding of fluid from the platform supporting lift whereby the platform gradually lowers in ratio to the building up of the height of the stack to maintain the top of the stack at the desired sheet reception level.

A further object of the invention is to so arrange the pneumatic control that it consists of a source of air under pressure and from which air is piped to be ejected in the direction of the side of a stack of sheets being built up upon a stack carrying platform, the ejected air stream normally having an unobstructed flow across the top face of the top sheet and the pneumatic control devised to operate the hydraulic lift fluid bleeding valve mechanism under changes of air pressure in the control; such changes in air pressure being brought about by relatively slight changes in back pressure in the air pipe delivering air for ejection and resulting from the building up of one or several sheets upon the top of the stack whereby an obstruction against the free ejection of air is constituted and sets up a back pressure to actuate the pneumatic control and so lower the platform to a point wherein the top sheet of the stack is below the path of the ejected air stream and has ceased to be an obstruction.

With the foregoing and other objects in view, as shall appear, the invention consists of a control device constructed and arranged all as hereinafter more particularly described and illustrated in the accompanying drawing in which the figure is a schematic view of the invention as used in governing the height level of stacked steel sheets.

In general strip mill practice, the sheared to size steel sheets are delivered on a conveyor (not shown) to be successively dropped unto the top of a stack of sheets 2

2

being built up; the space within which the stack is formed being bounded by a suitable open topped enclosure 3 and the stack carried upon a platform 4 mounted upon a ram 5 of a hydraulic lift cylinder 6. To move the ram upwardly fluid is injected into the cylinder, as through the pipe 7 which is valve controlled in the usual manner. To permit the ram to lower, fluid is bled from the cylinder through an ejection pipe 8 and in prior practice the bleeding of fluid was manually controlled by an operator who maintained the top sheet of the stack 2 at the desired level.

In this invention the bleeding of fluid from the cylinder through the pipe 8 is under the control of a valve 9 actuated by a solenoid 10 energized by an electrical circuit 11; the actuation of the valve 9 being controlled by fluctuations in air pressure in a pipe delivering air to an air jet nozzle directed towards the top of the sheet stack 2, as shall now be described.

The air jet nozzle 12 is carried by one of the sides of the stack enclosure 3 and at a height substantially in line with the top face or edge of the top sheet of the stack, the nozzle being arranged to normally direct a jet of air across the top face of the top sheet. Compressed air is fed to the nozzle from any suitable source and through a standard pressure regulator 13 and volume regulating valve 14 and from where it passes through piping 15 to the nozzle.

A branch pipe 16 extends from the piping 15 to an air pressure actuated switch 17 controlling the electrical circuit 11, the switch being designed and adjusted to operate under comparatively slight changes in air pressure in the branch pipe 16.

Operation

When the top sheet of the stack 2 is at the required level air ejection through the nozzle 12 is unobstructed. However, when additional sheets are added to the top of the stack their side edges form an obstruction against free air flow from the nozzle, thus causing a slight back pressure in the piping 15 and branch pipe 16, which back pressure is sufficient to close the air pressure switch 17. Closure of the switch 17 energizes the solenoid 10 to open the valve 9 and permit fluid to bleed from the cylinder 6 through the pipe 8, whereupon the ram 5 gradually lowers until the side edges of the several top sheets are below the path of air ejection from the nozzle. Immediately this occurs the back pressure in the piping 15 and branch pipe 16 is relieved with the resultant reduction of air pressure against the diaphragm 18 of the air pressure actuated switch 17 and permits the switch to open under the pressure of the spring 19. The consequent de-energization of the solenoid 10 allows the plunger 20 to move downwardly and close the valve 9 to cut off passage of fluid being bled from the hydraulic cylinder 6. As further sheets are delivered to the stack 2 the stack lowering operation repeats. To provide for any desired height adjustment the portion 15A of the piping is made of flexible material to permit adjustment of the nozzle 12 in the stack enclosure.

What I claim as my invention is:

1. In a device for controlling the height level of a stack of sheets carried upon a downwardly moveable platform supported by a hydraulic hoist and wherein the stack is built up by successively placing sheets upon the top of the stack and the platform lowered by bleeding fluid from the hoist; a source of compressed air and air piped therefrom to be ejected as an air stream at a predetermined stack top level and normally flowing substantially across the top of the stack, means controlling the bleeding of fluid from the hoist and actuated for the bleeding of fluid by back pressure against the free flow of the piped air and which back pressure is produced

三

by retardation of the flow of the ejected air stream through its impingement against the top portion of the side of the stack of sheets as they are being built up.

2. A device as claimed in claim 1, wherein the means for bleeding fluid from the hoist comprises a solenoid actuated valve, an electric circuit to the solenoid actuated valve, an air pressure actuated switch in the circuit and controlling energization of the solenoid, the air

5

2

pressure actuated switch being connected to the piped air and operable under back pressure against the free flow of the piped air.
